Primary Examiner — Sheryl Lane*(74) Attorney, Agent, or Firm* — Design IP(57) **CLAIM**

The ornamental design for a portion of a display screen with graphical user interface, as shown and described.

DESCRIPTION

FIG. 1 is a front view of a first embodiment of a portion of a display screen with graphical user interface showing my new design;

FIG. 2 is a front view of a second embodiment of a portion of a display screen with graphical user interface showing my design;

FIG. 3 is a front view of a third embodiment of a portion of a display screen with graphical user interface showing my new design; and,

FIG. 4 is a front view of a fourth embodiment of a portion of a display screen with graphical user interface showing my design.

The broken line showing of a portion of a display screen in FIGS. 1 through 4 forms no part of the claimed design. The broken line showing of text and portions of the graphical user interface in FIGS. 1 through 4 represents environmental subject matter and forms no part of the claimed design. The greyscale shaded portion of the claimed horizontal bar represents a shade that is different and/or darker than the unshaded portion of the claimed horizontal bar.

1 Claim, 4 Drawing Sheets**FIG. 1**

FIG. 2

FIG. 3

FIG. 4
